H. W. KISH

SELF FILLING FOUNTAIN PEN

Filed Nov. 19. 1924

Inventor
Herbert W. Kish

Thomas Donnelly
Attorney

UNITED STATES PATENT OFFICE.

HERBERT W. KISH, OF CHICAGO, ILLINOIS.

SELF-FILLING FOUNTAIN PEN.

Application filed November 19, 1924. Serial No. 750,771.

To all whom it may concern:

Be it known that I, HERBERT W. KISH, a citizen of the United States, residing at Chicago, in the county of Cook and State of Illinois, have invented a new and useful Improvement in a Self-Filling Fountain Pen, of which the following is a specification.

My invention relates to a new and useful improvement in a fountain pen and has for its object the provision in a self filling fountain pen of a reserve reservoir for containing writing fluid such as ink or the like, which may be used for writing purposes at the will of the user. It frequently happens that one using a fountain pen when writing, exhausts the ink or writing fluid contained in the reservoir of the fountain pen before finishing the writing which has been started, necessitating, in order to finish the writing, a refilling of the reservoir of the pen. It is often, in refilling the pen, impossible to obtain a writing fluid which, when used, presents a similar appearance to the appearance of the writing fluid previously used in the pen, resulting in an unfavorable appearance in the writing. In order to eliminate this objectionable feature, I have provided a reservoir for containing reserve writing fluid, and which may be filled at the same time the main reservoir is filled, and then closed from communication with the main reservoir so that the contents of the reserve reservoir may not be used until communication with the main reservoir is established by the one using the pen. Under ordinary conditions this would not be done except to complete writing an article already begun, so that sufficient ink of the same color and ingredients would be provided to finish the writing as was used in beginning it.

In self filling fountain pens it is quite customary to utilize a rubber sack as a reservoir to contain the writing fluid. With the use of my invention to provide a reserve reservoir, where a rubber sack is used as a container of the writing fluid, it is desirable that the sack be reenforced. This reenforcement is shown in the drawings as positioned at that point in the sack where the reserve compartment is closed from the main reser-

voir. However, the employment of the reinforcement may be extended throughout the length of the tube if desired.

It is also an object of the invention to provide a means for locking the device which closes the reserve compartment from communication with the main reservoir in locking position, so that the communication between the reserve compartment and the main reservoir may not be accidentally established.

Other objects will appear hereinafter.

The invention consists in the combination and arrangement of parts hereinafter described and claimed.

The invention will be best understood from a reference to the accompanying drawings which form a part of this specification and in which,

Fig. 1 is a side elevational view of a fountain pen embodying the invention,

Fig. 2 is a side elevational view showing the invention applied to a fountain pen with a part removed and a part in section,

Fig. 3 is a fragmentary vertical sectional view of a fountain pen embodying the invention showing the locking device in operative position,

Fig. 4 is a sectional view taken on substantially line 4—4 of Fig. 3,

Fig. 5 is a fragmentary view, in section, illustrating the method of locking the locking mechanism in operative position,

Fig. 6 is a fragmentary vertical sectional view of a modified form of the invention, showing one end of the sack reenforced with its own material and having a restricted neck,

Fig. 7 is a view similar to Fig. 6 with reinforcement embedded in the sack,

Fig. 8 is a fragmentary sectional view of a modified form.

The fountain pen is provided with a barrel 9 in which is positioned a rubber sack 10 adapted for the reception of writing fluid. This rubber sack is in communication with the forward portion 11 of the fountain pen, the connection being made in the usual manner. As shown in Fig. 2, a plurality of small wires 12 are embedded in the sack 10, adjacent the closed end, these wires extend-

2
ing longitudinally of the sack. Mounted in an opening formed in the barrel 9 is a sleeve 13 having a flange 14 which is adapted to lie in engagement with the periphery of the 5 barrel 9. Slidably mounted in the sleeve 13, with a slight play, is a stem 15 having a head 16 mounted thereon. Formed in the stem 15, as shown in Fig. 5, is a notch 17 which is adapted to receive an inwardly 10 projected tongue 18, punched from one side of the sleeve 13. Mounted on the inner end of the stem 15 is a semispherical presser foot 19.

The fountain pen is filled in the usual 15 manner by means of the presser lever 20. In filling the pen the presser foot 19 is moved to the position shown in Fig. 2. When the tongue 18 is disengaged from the notch 17, the tube or sack 10 will move the 20 presser foot into the position shown in Fig. 2. The sack is then filled in the usual manner by operating the presser lever 20. In filling these sacks or tubes, in fountain pens, there is generally left a slight space which is 25 not filled with the writing fluid. Subsequently to filling the sack in this manner, the pen is raised in upright position, permitting the writing fluid contained in the sack to flow toward the closed end of the sack. 30 The plunger 15 is then pressed inwardly so as to close a portion of the tube, adjacent its closed end, from the remainder of the tube, to provide a reserve compartment or reservoir. The slight unfilled space in the sack 35 will prevent any of the writing fluid being forced out of the sack when the reserve compartment is being shut off from the rest of the sack. This reserve compartment comprises a small portion of the sack, the main 40 body of the sack being used for the main reservoir. When the plunger 15 is pressed inwardly the tongue 18 engages in the notch 17 to prevent any accidental withdrawal of the presser foot 19 from engagement, in locking 45 position, with the sack 10.

After the contents of the main reservoir have been used and it is desired to continue the use of the pen with the same kind of ink, a slight movement of the stem 15, radially 50 of the sleeve 13 will disengage the tongue 18 from the notch 17 and permit the movement of the presser foot into the position shown in Fig. 2 so as to bring the two compartments into communication and permit 55 the use of the ink in the reserve compartment for writing purposes. When the compartment is sealed from the main reservoir the presser foot will be in the position shown in Fig. 4.

60 In Fig. 6 I have shown a modified form of the invention, in which the sack 9 has a portion adjacent the closed end reenforced from the same material from which the sack is made, by forming the reenforced portion 65 of greater thickness than the main body of

the sack. As shown in Fig. 6 and Fig. 7, the tube may be restricted, as at 21, the presser foot 19 engaging the tube at the restricted portion. The construction is such that the tube will be provided with a neck 70 portion, so that the walls of the tube will have less distance to be moved toward each other in order to close the reserve compartment from the rest of the tube. The restricted portion shown in Fig. 7 is reenforced by wires 12, which are preferably made from small pieces of copper wire, the small pieces being embedded around the sack and in alignment longitudinally extending 75 rows.

In Fig. 8 I have shown a modified form of the invention in which the tube 10 is provided with the restricted portion 22. Pivotally mounted on the barrel 9 is a lever 23 having an angularly extending portion 24, 80 carrying a narrow presser foot 25. The construction is such that when the lever 23 is lying in the position shown in Fig. 8, the reserve compartment will be closed from communication with the main reservoir. When the lever 23 is moved into upright position the presser foot 25 will be swung out of locking engagement with the sack 9 so as to permit communication of the reserve 85 compartment with the rest of the sack. 90

Various other modifications might be made to carry out the purposes of the invention and it is intended that these modifications shall come within the scope of the appended claims, which are drawn to cover 100 the invention generally.

Having thus described my invention what I claim as new and desire to secure by Letters Patent is:

1. A flexible writing fluid container adapted for use with fountain pens having reinforcing wires embedded and extending longitudinally thereof. 105

2. A flexible container for writing fluid adapted for use with fountain pens having reinforcing wires embedded therein. 110

3. In combination with a fountain pen having a flexible fluid container, a presser foot, and means for moving said presser foot into engagement with said container for dividing the same into a pair of non-communicating compartments, said presser foot being movable at will to open communication between said compartments. 115

4. In combination with a fountain pen having a flexible fluid container, presser adapted for movement into an engagement with said container for dividing the same into a pair of non-communicating compartments. 120

5. In combination with a fountain pen having a flexible fluid container a sleeve mounted on said pen; a stem projected slidably through said sleeve; a presser foot mounted on the inner end of said stem adapted for movement into engagement 125

with said container for dividing the same into a pair of non-communicating compartments.

6. In combination with a fountain pen having a flexible fluid container a sleeve mounted on said pen; a stem projected slidably through said sleeve; a presser foot mounted on the inner end of said stem adapted for

movement into engagement with said container for dividing the same into a pair of 10 non-communicating compartments; and means for engaging said stem for retaining said presser foot in said engaging position.

In testimony whereof, I have signed the foregoing specification.

HERBERT W. KISH.
